UNITED STATES PATENT OFFICE.

IRA W. KNIGHT, OF CRANSTON, RHODE ISLAND, ASSIGNOR TO GENERAL FIRE EXTINGUISHER COMPANY, OF PROVIDENCE, RHODE ISLAND, A CORPORATION OF DELAWARE.

DRY-PIPE SPRINKLER SYSTEM.

Application filed December 9, 1924. Serial No. 754,848.

This invention relates to improvements in dry pipe sprinkler systems having a booster pump for providing a sufficient operating head to insure adequate sprinkler discharge. 5 More especially it relates to apparatus for effecting the operation of said pump before dry pipe valve opens, whereby its tripping may be hastened and the discharge accelerated.

10 In my pending application Serial No. 754,847 there is disclosed a system in which the actuation of the booster pump is dependent upon the tripping of the dry pipe valve, there being a pressure responsive 15 device which effects starting of the pump motor upon rise of pressure in the intermediate chamber of that valve. In places where the water pressure supply is extremely low, or when it is greatly reduced 20 by adjacent fire engine or other pumps; a sufficient rise of pressure to effect pump actuation may not occur in the intermediate chamber; or it may be much delayed, due to the necessity of bleeding the air pressure to 25 practically zero, before the pressure is low enough to let the valve trip.

The present invention is to cause earlier starting of the pump, thus to bring about the positive opening of the dry pipe valve 30 irrespective of the supply pressure. A feature is the arrangement and combination of circuits through an accelerator which responds to a drop in pressure in the distributing line, and through a circuit closer 35 which responds to a rise of pressure, to the end that each device may perform its individual function without interfering with the other, and yet the separate actions of both shall combine to produce early and continuous operation of the pump.

Apparatus by which the invention may be practiced comprises the usual supply and distributing piping with a dry pipe valve and a booster pump interposed between the 45 supply main and the valve. The pump is driven by an electric motor whose current passes through a starting and controlling rheostat the actuation of which rheostat is in turn subject to a shunt circuit from the 50 main power wires. This shunt circuit may be set open or closed by the armature of a solenoid the energization of which may be effected by either a pressure fall device attached to the distributing pipes, or by a pressure rise device which may for example be

connected with the intermediate chamber of the dry pipe valve and normally open to atmosphere as disclosed in my said pending application. This double control is accomplished by arranging the energizing circuit 60 in parallel through these two devices so that the closure of either establishes current flow.

The accelerator of the present invention is connected with the system on the air side of the dry pipe valve and may be set to respond when the air pressure has fallen to a predetermined degree which may either be that at which the dry pipe valve would open if there were present a normally sufficient and desirable water pressure, or if desired 70 may be somewhat in excess of that, in which case the same effect is gained as if there were a high water pressure. The bleeding of the air system through an open sprinkler head down to this pressure operates to close the 75 energizing circuit, and so to effect operation of the pump. This properly builds up water pressure against the still closed dry pipe valve, and causes it to open which thus occurs long before the air pressure has gotten down to the level corresponding to the 80 actually low water pressure. The flow of water into the valve chamber also fills the branch pipe leading to the circuit closer which responds to rise in pressure, and operates it to throw its switch. Thus, the energizing circuit is doubly closed, as it were, by the switch of the accelerator, or pressure fall device, and also by the switch of the 85 pressure rise device. The pressure built up in the distributing pipes will open the accelerator switch, which started the pump, when it exceeds the degree at which that device operated to close the switch during 90 the fall of air pressure; but the re-opening 95 of this switch does not stop the pump because the pressure rise device, having already operated, keeps the energizing circuit closed. Thus the pump action, initiated by pressure fall, is maintained notwithstanding the ensuing pressure rise, giving a 100 continuous water pressure supply to the sprinkler.

It is intended that the patent shall cover, by suitable expression in the appended 105 claims, whatever features of patentable novelty exists in the invention disclosed.

In the accompanying drawings the single figure is an elevation showing a booster 110 sprinkler system embodying the invention,

parts being shown somewhat diagrammatically.

Referring to the drawings, the supply main 10 leads to a booster pump 12 which 5 discharges into the riser 14 leading to the dry pipe valve 18. As illustrated this valve is of the differential type, although the application of the invention is not limited to that, in which a water clapper 16 holds 10 back the water in riser 14 so long as the pressure upon the clapper 20 of air in the distributing pipes 22, is great enough, and until said pressure is reduced by escape of air through the sprinkler heads 24, when one 15 or more is opened.

The opening of the dry pipe valve permits the water to flow into its intermediate chamber, thereby closing its vent 26 which is normally open to atmosphere, and thence 20 through a small pipe 28 to a device 30 in which a switch 32 is operated by rise of pressure to close a circuit from the source of energy 34 through solenoid 36. The armature of the latter when drawn upward 25 upon energization of the solenoid rests across terminals 38 of a shunt circuit S whose current controls the operation of rheostat 40. This in turn governs the operation 30 of the motor 42 which drives the booster pump 12.

If the supply pressure in main 10 and 35 riser 14 were very low, due perhaps to other demands being made upon the supply, the bleeding reduction of the air pressure might not effect a tripping of the dry pipe valve or might be very long in doing so, and consequently the booster pump would not be started by the pressure rise device. To prevent this, the present invention provides 40 another circuit closer 44, herein called an accelerator, connected to the distributing line 22 beyond the dry pipe valve on the air side. This operates upon fall of pressure to close a switch 46 which forms part of the energizing circuit through the solenoid 36. This part of the circuit is arranged in 45 parallel with that part which passes through the other circuit closer 30, so that if either switch is closed, the circuit from the battery through the solenoid will be made. Since the accelerating device operates upon fall of pressure in the distributing pipe to close its switch and thus to effect pump operation, it acts oppositely upon rise 55 of pressure and opens the switch. But before its opening can thus occur, the pressure generated by the booster pump will have opened the dry pipe valve and caused the pressure rise device 30 to close its switch. 60 Thereafter it will not matter that the switch of the pressure fall device is opened by the elimination of the low pressure condition, for the circuit through the solenoid will still be closed and the pump thus be continued 65 in motion.

The starting of the pump is effected by the pressure fall device ahead of the opening of the dry pipe valve, whenever the air pressure has been reduced following the opening of a sprinkler head to a degree 70 which may be predetermined to give as early or late response as desired. By this means, in a locality where the city water pressure is low or is liable to fail, but where the pump 12 is capable of boosting the 75 pressure to a certain known standard at the dry pipe valve, the accelerator 44 can be set so that the valve will open when the air has fallen to one-sixth of that pressure (assuming the valve to operate on a 6 to 1 80 ratio of water pressure to air pressure) without waiting for the air pressure to drop to one-sixth of the actual city water supply pressure. This makes the action of the system analogous to that of a system 85 having the said standard of pressure actually available in the city supply. Once started, the pump is maintained running by the pressure rise device, so that an effective 90 discharge will be continuous until the system is reset.

I claim:

1. A sprinkler system having the combination, with a dry pipe valve and a booster pump, of pump control means having a connection with the system on the air side of said valve and another connection with the system on the delivery side of the pump, and comprising devices responsive to pressure changes in the system adapted upon the fall of pressure on the air side of said valve to initiate actuation of the pump and upon rise of pressure on the delivery side of said pump to maintain the pump actuation. 100

2. A sprinkler system having the combination, with a dry pipe valve and a booster pump, of pump control means including an electromagnetic device having two circuit closers; a pressure responsive device connected to the system on the air side of said dry pipe valve and adapted upon fall of pressure in said pipes to set one of said circuit closers whereby the pump is put in operation, and another pressure responsive device connected to the system and adapted upon rise of pressure therein to set the other of said circuit closers so as to continue the position of the electromagnetic device and maintain pump operation after the first said pressure responsive device has been made ineffective therefor by rise of the system pressure. 110

3. A sprinkler system having the combination, with a dry pipe valve and a booster pump, of pump control means including an electromagnetic device having two circuit closers; a pressure responsive device connected to the system on the supply side of the air clapper of said valve normally open 125

to atmosphere and adapted upon rise of pressure in the system to set one of said circuit closers to effect operation of said pump; and another pressure responsive device connected to the system on the air side of said clapper and adapted upon fall of system pressure to a predetermined degree above the atmosphere to set the other circuit closer for effecting pump operation, thereby causing a rise of pressure in the system to which the first mentioned device responds to effect continuation of said pump operation.

Signed at Providence, Rhode Island, this 17th day of October, 1924.

IRA W. KNIGHT.
